UNITED STATES PATENT OFFICE.

IVAN C. BELL, OF DALLAS, TEXAS, ASSIGNOR TO THE GUIBERSON CORPORATION, OF DALLAS, TEXAS, A CORPORATION OF DELAWARE.

DRILL-BIT REAMER AND GAUGE.

Application filed May 28, 1926. Serial No. 112,251.

This invention relates to new and useful improvements in drill bit reamers and gauges.

The object of the invention is to combine with the gauge rollers shown in my co-pending application filed May 14, 1926, Serial No. 109,037, reaming cutters projecting beyond the gauge faces of said rollers so that the hole will be reamed after the disk cutters, but the gauge rollers will operate to suspend cutting when the disks become out of gauge.

A further object of the invention is to provide a simple construction by combining the cutters and gauges in single rollers mounted on diametrically opposite sides of the body of the bit.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a view partly in section and partly in elevation showing a bit equipped with reaming and gauge rollers constructed in accordance with my invention,

Fig. 2 is a side elevation of the same,

Fig. 3 is a horizontal cross-sectional view taken on the line 3-3 of Fig. 1, and

Fig. 4 is a horizontal cross-sectional view taken on the line 4-4 of Fig. 1.

In the drawings the numeral 10 designates a bit body or stock, which has a tapered screw-threaded pin 11 at its upper end. At its lower end the body is shouldered and provided with a depending tongue 12. The sides of the stock are provided with vertical seats 13 and cheek plates 14 are engaged therein and secured by transverse bolts 15 and nuts 16. These plates engage under shoulders 17 at the upper portion of the stock. Laterally offset axle members 18 have circular cutting disks 19 journaled thereon and are suitably supported by the tongue 12 and the lower ends of the cheek plates. It will be noted that the cheek plates have their sides tapered downwardly and the stock is reduced at right angles to the axles so as to give the disks sufficient projection to cut freely. The exact construction of the bit is immaterial as my invention may be applied to any bit having a projecting cutter.

In each cheek plate between the bolts 15 I

provide a recess or cavity 20 which is bisected by a vertical bore 21 extending downward from the upper end of the plate. A cylindrical pin or shaft 22 is driven down this bore so as to lie between the openings 60 receiving the nuts 16 and having a snug fit. On each pin is journaled a gauge roller 23 having its lower edges bevelled at 24. This roller is journaled in the cavity 20 and projects a short distance beyond the surface of 65 its cheek plate 14.

On the upper portion of the face of each roller I form a plurality of vertical cutting ribs or teeth 25 projecting beyond the smooth or gauge face of the roller. These teeth may 70 be given any particular angularity or bevel according to the best practices in the field. Reaming cutters are quite common and the particular shape of the teeth is not a part of this invention. The upper and lower edges 75 26 of the teeth are beveled. The teeth will cut in an orbit as large or slightly larger than that cut made by the disks 19, thus reaming the hole as it is drilled.

By observing Fig. 3 it will be seen that the 80 cutting diameter of the disks is greater than the diameter or distance from the outer or gauge surface of one roller to the outer or gauge surface of the other roller, and, therefore, these gauge surfaces of the rollers do 85 not contact with the side walls of the hole while the disks are cutting or drilling. It will be obvious that as the cutting edges of the disks wear the diameters of said disks will be reduced, thereby reducing the cutting 90 diameter or circle of the bit. It is pointed out that the disks would continue to wear and after reaching a certain diameter the lower ends of the cheek plates 14 would begin riding on the sides of the hole which 95 would be tapered, and said plates would soon be worn to the point where they would be useless and in fact the whole lower end of the drill might be ground off. The gauge rollers 23 will prevent this because when the 100 disks wear to a predetermined diameter, said rollers will begin riding on the sides of the hole, thus rotatably supporting the bit and preventing further wear or cutting of said disks. The driller will soon observe that the 105 drill is not cutting and will be thus informed that his bit is out of gauge. The disks, cheek plates and bit stock will thus be saved from injury and the bit can be pulled up and new cutters supplied.

It is pointed out that if the cutters did tend to function after the rollers engaged the walls of the hole, the lower portion of the hole would be tapered by the continued wearing of said disks and the rollers would then prevent further advance of the bit so that the cutting and wearing of the disks would be stopped at this point and no injury done.

10 While I have shown and described the invention as applied to disk bits, it is to be understood that it may be applied to any drill bit having a projecting cutter at its lower end, either fixed or movable, and the invention is not to be limited to cutting disks or movable cutters.

Various changes in the size and shape of the different parts, as well as modifications and alterations, may be made within the 20 scope of the appended claims.

What I claim, is:

1. In a drill bit, a bit stock, a cutter carried at the lower end of the stock, a pair of gauge rollers having non-cutting faces 25 mounted on the stock and projecting therefrom, and reaming teeth extending from said rollers free from the faces thereof.

2. In a drill bit, a bit stock, oppositely disposed cutters carried by the stock, a pair 30 of oppositely disposed gauge rollers mounted on the stock above the cutters and projecting beyond the stock, said rollers being confined within a circle of less diameter than the drilling circle of the cutters, and reaming

teeth on the rollers segregated from the 35 gauge faces thereof and projecting beyond said faces.

3. In a drill bit, a bit stock, a plurality of oppositely disposed and laterally offset cutter disks mounted on the stock, means 40 on the stock for engaging the side walls of the hole and for supporting the bit in non-drilling position when said disks wear to a predetermined minimum diameter, and reaming cutters contiguous to said means. 45

4. In a drill bit, a bit stock having seats along opposite sides, vertical supports secured in said seats, a central support, rolling cutters journaled between said supports, said vertical supports having cavities in 50 their outer sides, gauge rollers journaled in the cavities of said vertical supports and projecting beyond the outer surfaces of said vertical supports, and reaming teeth extending from a portion of the vertical surface of 55 each roller.

5. In a drill bit the combination of a bit stock and check plates fitted against the stock, a pair of fastening devices passing 60 transversely through the stock and plates, reaming and gauge rollers journaled in the sides of the plates, and vertical shafts on which the rollers are mounted disposed in the plates and confined against vertical movement by said fastening devices. 65

In testimony whereof I affix my signature.

IVAN C. BELL.
